UNITED STATES PATENT OFFICE.

EDWARD W. STIFEL, OF WHEELING, WEST VIRGINIA.

DESIGN FOR A TEXTILE FABRIC.

48,407.

Specification for Design.

Patented Jan. 4, 1916.

Application filed May 15, 1915. Serial No. 28,473. Term of patent 14 years.

To all whom it may concern:

Be it known that I, EDWARD W. STIFEL, a citizen of the United States, residing at Wheeling, in the county of Ohio and State of West Virginia, have invented a new, original, and ornamental Design for Textile Fabrics, of which the following is a specification, reference being had to the accompanying drawing, in which the figure shows

a piece of textile fabric bearing my new design.

I claim:

The ornamental design for a textile fabric, as shown.

EDWARD W. STIFEL.

Witnesses:

H. E. DUNLAP,

W. F. KEEFER.
